UNITED STATES PATENT OFFICE

109,372

DESIGN FOR A DRESS

Harry Goldman, New York, N. Y.

Application March 18, 1938, Serial No. 75,919

Term of patent 3½ years

To all whom it may concern:

Be it known that I, Harry Goldman, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The stem portion of the attached flower, as shown, is appliqued to the waist section.

I claim:

The ornamental design for a dress, substantially as shown, and described.

HARRY GOLDMAN.
